COMBINATION COKING AND CATALYTIC CRACKING PROCESS

Joseph K. Roberts, Flossmoor, Ill., assignor to
Standard Oil Company, Chicago, Ill., a corpora-
tion of Indiana

Application May 27, 1938, Serial No. 210,316

11 Claims. (Cl. 196—49)

This invention relates to a combination coking and catalytic cracking process, and it pertains more particularly to an improved method for the manufacture of high quality motor fuels from petroleum and petroleum products.

An object of the invention is to obtain maximum yields of high quality motor fuel from petroleum oils, including oils derived from shale, coal, lignite and other carbonaceous materials and products thereof. More particularly, the object is to produce a motor fuel characterized by a high octane number—a fuel which will have a minimum tendency to knock when used in high compression spark ignition internal combustion engines. A further object is to produce such a fuel which is free from corrosive sulfur and which may be easily stabilized against oxidation and gum formation, which will have a high blending value and a good lead tetraethyl response, and, in short, which will meet all of the rigid specifications for a high quality motor fuel.

A further object of the invention is to provide a new and improved method and means for combining a thermal coking process with a catalytic conversion process, whereby each process may be operated with maximum effectiveness and efficiency. A further object is to remove coke-forming materials from charging stock to a catalytic cracking process so that the catalyst may be operated for a longer period of time or for the production of larger yields of gasoline before necessary shutdowns for regeneration.

A further object is to subject "dirty" (coke-forming) components of charging stock from the fresh feed to a coke furnace in combination with low gravity residues from the coking and/or cracking processes, so that maximum gasoline yields may be obtained from such stocks. A further object is to subsequently treat the liquid products from the coking step to improve their knock rating characteristics, lower their sulfur content and improve their value as high quality motor fuels.

A further object is to integrate a coking system with a catalytic cracking system whereby optimum temperatures and pressures may be employed in all parts of both systems, and whereby the products from each system may be most effectively utilized for the production of maximum yields of high quality gasoline. Other objects will be apparent as the detailed description of the invention proceeds.

Gasolines and gas oils produced by coking

operations are usually more paraffinic (and hence are characterized by lower knock ratings or octane numbers) than those of gasolines and gas oils produced by high pressure thermal cracking systems. In practicing my invention I introduce the products from the coking drums at a temperature of about 750 to 900° F., preferably about 825° F., into a flash drum into which I also introduce a fresh feed which has been preheated to a temperature of incipient cracking, i. e., about 700 to 800° F. The coking drum products supply additional heat to the introduced feed and the gases from the coking drum help to strip out the gasoline and light gas oil fractions from the liquids in the flash drum so that substantially all of the light gas oil is separated from the heavy residual products. These heavy residual products are returned to the coking operation; and the light gas oil, either with or without the naphtha fraction, is heated to about 850 to 1000° F., preferably about 925° F. to 950° F. and passed through a catalytic cracking chamber. This catalytic cracking step converts the mixture of fresh feed, light gas oil and coking drum light gas oil either with or without the naphtha from both sources into high quality motor fuel which is characterized by a specially high octane number. The products of the catalytic cracking are then fractionated, the gasoline fraction is stabilized and the cycle stock is either returned to the flash drum or directly to the coking furnace.

As catalysts for my process I may employ acid-treated bentonite, or other activated hydro-silicate of alumina, particularly combinations in which the ratio of silica to alumina is about 4:1. The catalyst may be prepared by depositing alumina or oxides of other metals such as copper, cadmium, cerium, nickel, boron, etc. on silica gel. I may also employ catalysts of the type represented by aluminum silico fluoride, $Al_2(SiF_6)_3$. I may use metal oxide catalysts on any suitable carriers. I may also use catalysts of the so-called homogeneous type, as exemplified by butyl bromide and other alkyl halides, either alone or in combination with the heterogeneous catalysts hereinabove referred to.

The invention will be more clearly understood from the following detailed description, and from the accompanying drawing which forms a part of this specification and in which I have shown a preferred modification of a flow diagram of the improved process.

The invention is applicable to the production of high quality motor fuel from all types of min-

eral oils or oils obtained by the destructive distillation, hydrogenation, carbon monoxide reduction or catalytic conversion of carbonaceous materials and in my preferred example I will describe the application of the process to a reduced crude charging stock. The invention is also applicable to slop refinery cuts, gas oils (particularly cycle or "dirty" gas oils), naphtha or mixtures of some or any of the stocks which are commonly produced in petroleum refineries.

The fresh feed is introduced by pump 10 through line 11 and preheating coils 12 of pipe still 13, thence through line 14 to flash drum 15. The oil is preferably heated in coils 12 to incipient cracking, i. e., to a temperature of about 700 to 800° F. It should be understood that any suitable type of preheater may be employed for this purpose, and that the temperature of preheating will depend upon the particular stock charged and the heat balance of the unit.

The flash drum is preferably operated at about 50 to 100 pounds per square inch, and it is provided with conventional baffle plates or bubble plates. The temperature conditions in this drum are maintained to effect the separation of light gas oil, naphtha, gasoline and gases from heavy gas oil and residue, the latter being withdrawn from the base of the drum through line 16 and forced by pump 17 through coils 18 of coking furnace 19, the oil being discharged through line 20 and one of the branched lines 21, 21' and 21'' at a temperature of about 900 to 950° F., into one of the coking drums 22, 22' or 22''. These coking drums are operated at about, or somewhat higher than the pressure of the flash drum, and the overhead products from the coking drum are withdrawn through lines 23, 23' or 23'' and line 24 back to the flash drum, preferably at a point below the introduction of fresh feed. The temperature of the vapors introduced through line 24 may vary from about 750 to 900° F., but this temperature is usually about 825 to 850° F. When materials in coking drum 22 are substantially reduced to coke this drum is cut out of the system and oil is introduced through line 21' to coking drum 22'. While the coke is cooling in drum 22, the coke in drum 22'' is being withdrawn through manhole 25''. The operation of these so-called "delayed cokers" is well-known in the art and further detailed description is therefore unnecessary.

The hot vapors returned through line 24 to flash drum 15 are partially condensed by the incoming feed stock and simultaneously these gases and vapors tend to effect the vaporization and stripping of light gas oil from the incoming feed stock. The entire mixture of light gas oil, gasoline and gases may be withdrawn from the top of flash drum 15 through line 26, passed through radiant or roof coils 27 of pipe still 13 to increase their temperature to about 850 to 1000° F., and then introduced through line 28 and one of the branched lines 29, 29' or 29'' into catalyst chamber 30, 30' or 30''. These catalyst chambers may be of any conventional type and may be diagrammatically represented as vertical drums containing beds of catalyst 31 supported on suitable trays 32. It should be understood, however, that I may employ a massive catalyst bed with perforated inlet and outlet pipes such as are employed in the so-called "Houdry process" or I may employ simple tubes packed with catalyst material. No novelty is claimed in the particular catalyst chamber and it will therefore not be described in further detail.

As catalyst material I may employ any known cracking catalysts, of which there are a large number. Activated hydrosilicate of alumina has been found to give excellent results, particularly when the ratio of silica to alumina is about 4:1. Such catalyst may be made from acid-treated bentonite by making a dough of such bentonite and water, forming pellets about $\frac{1}{8}$ to $\frac{1}{4}$ of an inch in diameter and thoroughly drying said pellets, preferably at temperatures of about 850 to 1000° F. I may, however, deposit alumina or other metal oxides on silica gel, i. e. sodium silicate may be precipitated with hydrochloric acid and washed free from chlorides and may then be impregnated with a solution of copper, cadmium or cerium sulfates or nitrates, nickel chloride, boric acid or other solutions of metal salts or acids, the catalyst being then thoroughly dried. Aluminum fluosilicate offers the advantage of relatively small carbon deposits. Butyl bromide or other alkyl halides or halogen acids may be used as promoters or homogeneous catalysts, either alone or in conjunction with the heterogeneous catalysts hereinabove described.

Vapors from line 28 are preferably passed through the catalyst chamber at a space velocity of about 0.25 to 2.0 volume of liquid feed per volume of catalyst space per hour. For light gas oils the preferred temperature is about 925° F., although higher temperatures may be used, particularly with higher space velocities. For lighter stock such as naphthas, the temperature should preferably be about 1000° F. The optimum temperature for any given stock may be determined by a few simple preliminary experiments.

The catalyst chambers, like the coking drums, are operated in sequence, one or more chambers being revivified while another chamber is on stream. The revivification may be effected by controlled oxidation with hot flue gases containing controlled amounts of oxygen and circulated through lines 33, 34, 34', 34'', 35, 35', 35'' and 36. These lines may also be used for purging the catalyst chambers of hydrocarbon liquids and gases prior to revivification and purging the chambers of regenerating gases prior to going on stream. The revivification is preferably effected at a temperature of about 1000 to 1050° F. and care should be taken to prevent undue temperature rises which might fuse or sinter the catalyst and thereby render it ineffective. Catalyst revivification is well known in the art and therefore needs no further detailed description.

Reaction products from the cracking chambers are withdrawn through lines 37, 37' or 37'' to line 38 and then introduced at an intermediate point of fractionating tower 39. This tower is provided with a suitable heating means at its base such as a steam coil or an external heater 40 through which the bottoms are circulated. Vapors from the top of the fractionating tower are withdrawn through line 42 and partial condenser 43 to separator 44 from which gases are withdrawn through line 45, a part of the liquids are returned as reflux through line 46 and the remaining liquid is withdrawn through line 47 to a stabilizer tower 48, or thru line 49 for further processing or finishing. The tower may be operated under conditions to withdraw heavy naphtha from side stream 50 for further processing. Stabilizer 48 is provided with suitable heating means at its base and reflux means at its top and may, in fact, be of conventional design, propane and lighter gases being withdrawn from the top thereof and sta-

bilized gasoline being withdrawn from the base through line 51.

The cracked cycle stock from the base of fractionating tower 39 may be withdrawn through line 52 and line 53 to line 16 for admixture with residue enroute from the base of flash drum 15 to the coking furnace (altho coking is not as desirable as cracking on stocks boiling below 300° F.). Alternatively, it may be introduced through line 54 to line 14 entering the flash drum, or through line 55 to line 10 for admixture with fresh feed. I have found that this cracked cycle stock is an excellent tractor fuel, particularly when combined with a portion of the liquids which are normally included in the gasoline, and the cracked cycle stock may therefore be withdrawn through line 56 for use in tractor fuel or for other purposes. It is particularly valuable as a charging stock for thermal cracking. I have found that thermal cracking is more effective than catalytic cracking for obtaining high gasoline yield from this particular stock.

The cracked and stabilized gasoline from line 51 may have an octane number of about 80 to 90, and is characterized by a very low sulfur content. It requires only a very light treating, is easily sweetened and may be effectively stabilized with a very small amount of antioxidant. It is an excellent blending fuel, and shows an excellent response to lead tetraethyl for further increase of octane number.

From the above description it will be seen that the fresh feed is practically all converted into cracked gasoline, coke and gases, the gasoline yield being in some cases as high as 76% on crude and 50% on reduced crude (from which 400° F. end point products have been removed). The gases may be polymerized to form still further quantities of high quality gasoline in a conventional polymerization system; or may be reacted with liquid hydrocarbons in a gas reversion process.

While I have described the passage of all of the gases and vapors from flash drum 15 through the catalytic conversion system, it should be understood that suitable bubble trays or other fractionating means may be employed in the top of flash drum 15 or in addition to flash drum 15 (such as a separate fractionating tower, not shown), so that selected fractions from the flash drum are separately passed through the catalytic cracking system. For instance, C₄ and lighter hydrocarbons may be withdrawn from the top of the flash drum (or other fractionator) through line 57 to a conventional polymerization or gas reversion system, and the mixture of gasoline and light gas oil may be withdrawn as a side stream through line 58 and forced by pump 59 through heating coil 27 and thence to the catalytic conversion system. Alternatively, the light naphtha and gases may be withdrawn through line 57 and only the heavy naphtha and gas oil fraction passed through line 58 to the catalytic conversion process. Since the optimum conversion conditions for naphtha are slightly different than those for gas oil, and since different catalysts may be used, I may separately collect the naphtha and light gas oil components from the flash drum, pass the gas oil components through the catalytic chambers at a temperature of about 925 to 950° F. and pass the naphtha fraction through different catalyst chambers at a temperature of about 1000° F. In any event, it will be seen that the relatively low knock rating naphthas and gas oils from the fresh feed

and from the coking drums are catalytically converted into motor fuels of high quality and particularly of high octane number.

While I have described in detail a preferred embodiment of my invention, it should be understood that I do not limit myself to such details except as defined by the following claims, which should be construed as broadly as the prior art will permit.

10 I claim:

1. The method of converting heavy hydrocarbons into high quality motor fuel, which comprises heating said hydrocarbons to incipient cracking and introducing said heated hydrocarbons into a flash zone, withdrawing hydrocarbons heavier than light gas oil from the base of said flash zone, heating the withdrawn hydrocarbons heavier than light gas oil to about 900 to 950° F. and introducing them into a coking zone, introducing gases and vapors from said coking zone into said flash zone for combination with the introduced fresh feed, and catalytically cracking the light gas oil fraction of the hydrocarbons withdrawn from the upper part of said flash zone 25 to produce a motor fuel of high octane number.

2. The method of claim 1 wherein the catalytic cracking is effected at a temperature of about 850 to 1000° F.

3. The method of claim 1 wherein the catalytic cracking is effected in the presence of a catalyst comprising silica and a metal oxide.

4. The method of converting heavy hydrocarbons into high quality motor fuel, which comprises introducing said hydrocarbons into a flash zone, continuously withdrawing hydrocarbons heavier than light gas oil from the base of said flash zone, increasing the pressure on the withdrawn hydrocarbons and introducing them into a coking drum at a temperature of about 900 to 950° F. whereby said hydrocarbons undergo decomposition to form coke, gases and vapors introducing the gas and vapors produced by the coking process into said flash zone for admixture with incoming fresh feed, withdrawing light gas oil, naphtha and gases from the upper part of said flash zone and catalytically cracking said light gas oil to produce high quality motor fuel of high octane number.

5. The method of claim 4 wherein the light gas oil from the flash zone is catalytically cracked in the presence of naphtha from the flash zone.

6. The method of claim 4 which includes the further steps of fractionating products of the catalytic cracking into gases, gasoline and cracked cycle stock, recycling said cracked cycle stock to the coking step and stabilizing the gasoline fraction.

7. The process of converting heavy hydrocarbons into high quality motor fuel which comprises preheating said hydrocarbons to a temperature below cracking temperature, introducing said preheated hydrocarbons into a flash zone, withdrawing liquids heavier than light gas oil from the base of said flash zone, heating said withdrawn liquids to a temperature of about 900 to 950° F., coking said heated liquids under a pressure of about 50 to 100 pounds per square inch to form coke and light hydrocarbon gases and vapors, returning said light hydrocarbon gases and vapors at a temperature of about 750 to 900° F., to said flash drum, maintaining said flash drum at substantially the same pressure as the pressure in the coking drum, withdrawing light gas oil from the upper part of said flash drum, heating said light gas oil to a temperature

of about 850 to 1000° F., contacting said heated light gas oil with a cracking catalyst to effect catalytic conversion thereof, and fractionating the catalytic conversion products into gasoline, a fraction heavier than gasoline, and gases respectively.

8. The method of claim 7 wherein naphtha is passed together with the light gas oil from the top of the flash zone through the heating step, catalytic conversion step and final fractionation step.

9. The method of claim 7 wherein the fractionated product heavier than gasoline is recycled to the coking step.

10. The method of claim 7 wherein the fraction heavier than gasoline is recycled to the coking step by way of the flash zone.

11. In a process of catalytic cracking wherein liquid hydrocarbons are contacted with a non-oxidizing cracking catalyst of the silica alumina type at a temperature of about 850 to 1000° F. and wherein a carbonaceous deposit accumulates

on the catalyst so that the catalyst requires periodic regeneration for removal of such deposits, the method of prolonging the activity of the catalyst and decreasing the frequency of required regeneration, which method comprises introducing charging stock into a flash zone, pumping heavy hydrocarbons including heavy gas oil from the base of said flash zone through a heating zone and heating said heavy hydrocarbons to a temperature of 900 to 950° F., introducing the heavy hydrocarbons at a temperature of 900 to 950° F. into a coking zone maintained at such temperatures that the introduced materials are converted into coke, gases and vapors, returning said gases and vapors from said coking zone to said flash zone, withdrawing light gas oil and lighter hydrocarbons from the upper part of said flash zone, and charging the light gas oil which is withdrawn from the upper part of said flash zone to said catalytic cracking process.

JOSEPH K. ROBERTS.
